(57) **CLAIM**

The ornamental design for an industrial oven, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front perspective view of the industrial oven, showing the new design.

FIG. 2 is a front view of the industrial oven of FIG. 1.

FIG. 3 is a rear view of the industrial oven of FIG. 1.

FIG. 4 is a top view of the industrial oven of FIG. 1.

FIG. 5 is a bottom view of the industrial oven of FIG. 1.

FIG. 6 is a right-side view of the industrial oven of FIG. 1.

FIG. 7 is a left-side view of the industrial oven of FIG. 1; and,

FIG. 8 is another front perspective view of the industrial oven of FIG. 1, with the front door opened.
